UNITED STATES PATENT OFFICE.

WILLIAM HENDERSON THOMPSON, OF MEMPHIS, TENNESSEE, ASSIGNOR TO THOMAS McC. SPARKS, WILLIAM M. SPARKS, AND GEORGE H. COLE, ALL OF RIPLEY, TENNESSEE.

PERFORATOR FOR PRINTING-PRESSES.

1,203,436.

Specification of Letters Patent.

Patented Oct. 31, 1916.

Application filed January 7, 1916. Serial No. 70,884.

To all whom it may concern:

Be it known that I, WILLIAM HENDERSON THOMPSON, a citizen of the United States, residing at Memphis, in the county of Shelby 5 and State of Tennessee, have invented a new and useful Perforator for Printing-PresSES, of which the following is a specification.

The present invention appertains to a perforator for printing presses, and aims to 10 provide a perforator of novel and improved construction, and applicable to a platen printing press, whereby the paper and other stock which is being imprinted, will be perforated simultaneously with the printing 15 operation.

It is also within the scope of the invention to provide a perforator for printing presses, which is improved generally in its construction and details, to enhance the utility and 20 efficiency thereof, the device being simple, substantial, compact, non-encumbering and inexpensive in construction, as well as being convenient, serviceable and practical in use.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

The invention is illustrated in the accompanying drawing, wherein:—

Figure 1 is a plan view of the perforator. Fig. 2 is a view illustrating the perforator, partly in elevation and the remainder in 40 longitudinal section. Figs. 3, 4 and 5 are enlarged sectional details taken on the lines 3—3, 4—4 and 5—5, respectively, of Fig. 2.

The present perforator embodies a bar or elongated stock 1 constructed of suitable metal or material, and having a widened or 45 enlarged basal portion 2, provided with an aperture 3 and lip 4 for attaching the basal or butt end 2 of the bar 1 to the gripper bar of the platen printing press, in order that the bar 1 will assume the position of the 50 ordinary gripper carried by the gripper bar, to coöperate properly with the type form and platen.

The bar 1 is provided with an elongated longitudinal slot 5 between its edges, in 55 which is movably or slidably disposed, an

elongated perforator blade 6. The blade 6 is disposed longitudinally within the slot 5, and one edge of the blade is serrated or toothed, as at 7, said toothed or active edge being disposed slidably within the slot 5, 60 while the other edge projects in the rear of the bar 1. The active edge of the blade may be properly formed for cutting perforations, cuts or scores in the paper, blank or other stock being printed upon. The active edge 65 of the blade is normally retracted within the slot 5, whereby the bar 1 can bear against the paper or other stock in the manner of an ordinary gripper.

The blade 6 is carried by a longitudinal 70 shoulder or bar 8 parallel with the bar 1 and co-extensive in length with the blade 6. The bar 8 is provided with a longitudinal channel or groove 9 in which the inactive edge of the blade 6 is fitted snugly, and screws 10 75 or other securing elements are engaged through the bar 8 and blade 6 to securely hold said blade in place relative to the bar 8.

In order to hold the bar 8 assembled with the bar 1 and to limit the movement of the 80 bar 8 relative to the bar 1, the bar 8 is provided adjacent its ends with pairs of apertures or bores 11 at the opposite sides of the blade 6, and said bar 8 is provided with outer counter bores 12. Screws or equivalent 85 elements 13 threaded or otherwise engage the bar 1 at the opposite sides of the slot 5 and pass slidably through the bores 11, and the free ends of said screws are provided with heads 14 working snugly within the 90 counter bores 12. The counter bores 12 are elongated, whereby when the bar 8 is brought against the bar 1, the heads 14 will still be within the counter bores 12, so that the screws will not project from the device 95 as would be objectionable. The screws 13 thus guide the bar 8 in its movement to and from the bar 1, and said screws also limit the separation of the bars in a satisfactory and efficient manner.

The bars are normally separated to retract the blade, and to this end leaf springs 15 have their remote ends riveted or otherwise fastened, as at 16, to the bar 1 beyond the ends of the slot 5 and at the same side 105 of the bar 1 as the bar 8. The leaf springs 15 project toward one another and are bent so as to flex away from the bar 1 when the parts are released. The free ends of the springs 15 have slots or bifurcated portions 110

17 receiving the ends of the blade 6, the free ends of the springs being disposed between the bars 1 and 8. The ends of the bar 8 are provided with inner cut away portions or 5 rabbets 18 in which the ends of the springs 15 work, whereby the bar 8 can move completely against the bar 1 without the interference of the springs with such movement.

In practice, the basal portion 2 of the bar 10 1 is attached to the gripper bar of the printing press, to occupy the position of one of the ordinary grippers, and this will cause the perforator to be properly or timely carried to position adjacent the type form 15 during the printing operation, and with the shoulder or bar 8 bearing against the furniture of the type form which is inserted to provide the blank space in the paper or stock which is to be perforated. The active edge 20 of the blade thus projects away from the type form, whereby the paper or stock carried against the form by the platen, will be brought into engagement with the active edge of the blade 6. When the platen is 25 moved adjacent the form for completing the impression, the shoulder or bar 8 in bearing against the wood furniture of the form, and the bar 1 being moved toward the shoulder or bar 8 by the platen, will cause the 30 bars 1 and 8 to be forced toward one another against the tension of the springs 15, and this will cause the blade to be pushed through and out of the slot 5 toward the paper or stock. As a result, the active edge 35 of the blade is projected to perforate the paper.

When the platen is retracted and the gripper bar returned to idle position, the perforator will, by reason of the pressure having been removed from the bars 1 and 8, be withdrawn from the paper or sheet, and the paper or sheet will thus be left smoothly upon the platen from which it is removed as usual by the press feeder. It is to be 45 noted that when the pressure upon the shoulder or bar 8 is removed, the shoulder or bar

will immediately spring away from the bar 1, to draw the blade into inactive position, with the active edge of the blade retracted within the slot 5. This will prevent the 50 paper or sheet from being pulled from the gage pins on the platen of the printing press after the imprint has been made, and the present device will therefore avoid the tendency of the sheet of paper adhering or sticking 55 to the perforator.

The present device thus enables the paper or stock to be perforated at the same time that the imprint is made upon the paper or stock, and the present device also acts as a 60 gripper, and eliminates the possibility of a slur being given to the printing upon the paper or stock.

The present device may be constructed in 65 various sizes, or proportions, according to the nature of the work to be done, and the active edge of the blade may be of different formations when various forms of perforations, slits or scores are to be made.

Having thus described the invention, what 70 is claimed as new is:—

A perforator comprising a bar having a slot, a blade having an active edge normally retracted within said slot and projectable therefrom, a second bar having a 75 channel in which the other edge of the blade is fitted, means for securing the blade within the second bar, the ends of the second bar having inner rabbets, and leaf springs secured to the first mentioned bar beyond the 80 ends of said slot and having their free ends working in said rabbets to move the bars apart, the free ends of the springs being slotted and receiving the ends of the blade.

In testimony that I claim the foregoing 85 as my own I have hereto affixed my signature in the presence of two witnesses.

WILLIAM HENDERSON THOMPSON.
